ARCH SUPPORT

Jacob P. Schnellbacher, Peoria, Ill.

Application December 20, 1934, Serial No. 758,395

9 Claims. (Cl. 36—71)

This invention has reference to arch supporters and has for its primary object the provision of an arch support adapted to be used in association with a shoe, capable of supporting portions 5 of the foot in a firm but resilient manner.

Another object lies in the provision of a supporter as aforesaid having convenient means for adjustment to the end that different portions of the foot may be supported in any manner that 10 is required for a particular injury or deformity.

Another object is to provide an arch supporter of the class described wherein the adjustable supporting elements are assembled and retained in a self-contained unit which is removable from the 15 associated innersole parts, whereby supporting elements of various sizes, forms and supporting power may be interchanged, for the purpose of applying modified support as required in the treatment of broken arches in the foot or other 20 deformities thereof.

A further object is to provide an arch supporter comprising an innersole and a removable arch supporting element adapted to be associated therewith.

Before proceeding with the description, it may be remarked that I am aware of numerous devices somewhat similar in form and function which have been placed upon the market, but I herewith present a device having particular utility and novelty of structure not found in conventional arch support devices.

It is well known that in cases where the metatarsal or other bones of the foot, with their associated muscles, become misplaced or weakened 35 the accepted method of readjustment includes placing a supporting means under the affected part for the purpose of supporting the bones in their proper relation, to thus remove a portion of the stress on associated weakened muscles and 40 tendons whereby the same may have rest and an opportunity to recuperate to the end that the difficulty may be permanently removed.

It is further well known that affections of the 45 instep portions of the foot vary widely as between individuals. With some, the affection may be of recent origin or incipient and therefore may require only a slight, resilient support, or the support may be required only in certain localities. On the other hand the affection may be of long standing and of serious extent so as to require a support sufficiently sturdy to meet requirements while at the same time being resilient as possible for comfort of the wearer.

It is with the foregoing in view that I provide 55

the device disclosed in the accompanying drawings, in which:

Fig. 1 is a plan view of my arch support device showing relative positioning of parts to be described;

Fig. 2 is a side elevational view of the same;

Fig. 3 shows the assembly as the same would appear installed in a shoe, viewed from the side opposite that shown in Fig. 1, with certain portions of the shoe broken away to permit clearer 10 view of underlying parts;

Fig. 4 is a side elevational view showing details of a removable unit portion of my invention, which will be described;

Fig. 5 is a sectional elevational view taken on 15 line 5—5 of Fig. 4;

Fig. 6 is a side elevational view of an element of the invention to be described;

Fig. 7 is a plan view of the part shown in Fig. 6; 20 and

Fig. 8 is an enlarged fractionated elevational sectional view showing details of the invention to be described.

Figs. 1 and 2 disclose my invention as generally comprising an innersole member 10 having a conformity adapting it to be placed in a shoe. The member 10 is preferably made from leather and is pre-formed to have an elevated portion 11 intermediate its ends and disposed at one side as illustrated. The elevated portion is so disposed as to have its highest part lie under the instep upon the inner side of the foot and to have its surface decline substantially therefrom on all sides to merge with the surface of the innersole. 25

A metal plate 12 is disposed to lie across the area below the portion 11 and is secured at each end to the innersole structure by any suitable means, such as pieces of leather 14 sewn to the innersole in such a manner as to form pockets to receive the ends of the plate. 30

Plate 12 is provided, as shown in Figs. 6 and 7, with a plurality of upstanding lugs 15. The lugs are so disposed upon the plate that when the plate is attached to an innersole, the lugs will lie in an upwardly directed position. The purpose 35 of the lugs will be explained shortly.

Figs. 4 and 5 illustrate a support unit comprising an envelope structure 16 having an open side 17. The envelope is fashioned on its upper side to substantially conform with the interior surface 50 of portion 11 of the innersole, while its lower side lies substantially flat as shown.

The body of the envelope is preferably made from a single piece of soft rubber or similar material. At the point where the upper and lower 55

portions meet the material is formed to provide a somewhat thick, wedge shaped edge 18.

Embedded in the envelope material are upper and lower plates 19 and 20. The upper plate 19 is fashioned to conform with the general contour of the upper portion of the envelope and the lower plate 20 lies flat as shown.

Fig. 4 illustrates that the envelope is adapted to receive and retain a plurality of coil springs 21 between its upper and lower walls.

Fig. 8 illustrates in detail that upper plate 19 is provided with inwardly directed perpendicular portions 22 and plate 20 is provided with similar portions 23.

15 Portions 22 and 23 are so arranged in the plates, and the plates are so arranged with respect to each other that the former lie in alignment and are adapted to act as retainers for springs 21 to hold the same in proper position in the envelope.

It is to be noted that the material of the envelope is so disposed as to completely cover the plate 19 together with the portions 22 and that there is formed in the envelope material annular 25 groove 24 surrounding the portions 22 whereby to provide cushioned recesses adapted to receive and retain the ends of springs 21 without contact between the springs and metallic portions of the plate.

30 Adjacent the lower plate 20, the envelope material is formed in a manner similar to that just described with the exception that the interior of portions 23 are left open and an opening is provided in the envelope material opposite the openings of the plate.

It will be apparent that portions 23 of plate 20, also portions 22 of plate 19, are so disposed as to register with lugs 15 of plate 12, and in Fig. 8 it is clearly shown that lugs 15 are of such proportions as to be received in the opening in portions 23 whereby, when the envelope unit is placed in suitable position upon plate 12, the lugs 15 enter the openings 23 to accomplish anchorage by means of which the envelope structure is removably anchored on the plate.

45 It will now become apparent that the envelope unit may be inserted in the space between plate 12 and elevated portion 11 of member 10 as shown in Fig. 2, to be firmly retained in position 50 by means of lugs 15. It will also be apparent that, due to the resilient construction of the device, the lower portion thereof may be raised sufficiently to disengage the unit from the lugs as indicated in dotted lines in Fig. 5, whereupon the 55 unit may be removed from the innersole.

60 It is to be noted that there is no attachment between plates 19 and 20 other than is provided by the envelope material and that plate 19 is in fact, a floating member held in suitable alignment with plate 20 by means of the envelope material and is resiliently supported to oppose vertical movement by springs 21 while at the same time the outer edges of the plate are 65 partially supported by the thicker edge portion 18 of the envelope. Thus the springs co-operate with the envelope material to support the elevated portion 11 of the innersole, in a resilient manner.

70 Since there is a layer of soft envelope material between all metal portions of the device, except between lugs 15 and plate 20, the device is entirely noiseless when in use.

75 With the envelope removed from the innersole it is quite obvious that the springs 21 may easily

be removed and interchanged with springs of different characteristics.

Fig. 1 illustrates that the springs are so disposed as to provide support at the particular points dictated by the anatomy of the foot.

5 Since springs of any desired strength may be easily and quickly placed in any one of the several positions shown, allowing frequent modification of various portions of the support, it is clear that my device provides an efficient means for progressive treatment of the foot afflictions noted.

10 Referring to Figs. 1 and 3, it is to be noted that plate 12 is so fashioned and disposed as to have its rear, or heel end 25 lie against the counter portion of the heel of the shoe, and its forward 15 end 26 lie against the upper of the shoe at a point beyond the arch thereof.

15 Between the two points noted the plate is cut away to approximately follow the conformity of the instep portion of the shoe.

20 It is well known that in practical use, devices of this kind tend to progressively move toward the inside of the shoe whereby that portion lying between the toe and heel presses against the soft upper leather of the instep portion. This portion is obviously not sufficiently stiff to oppose the side movement, with the result that the upper leather is often deformed sufficiently to destroy the symmetrical appearance of the shoe. Also, in the case just noted, the support element becomes misplaced in relation to the shoe and foot with resulting loss of efficiency.

25 With the arrangement herein described the side thrust of the device is applied at points in the shoe which have sufficient strength and firmness 30 to oppose sidewise movement, whereby the device is firmly held in proper position.

What I claim is:

1. A device of the class described including in combination an innersole member having an elevated portion, a plate member attached to the innersole at each side of the elevated portion and a unitary support element inserted between said plate and innersole, said support element comprising an envelope member made from resilient 45 material, said envelope having an open side and receptacles formed on opposite interior surfaces of two of its sides, said receptacles adapted to receive and retain resilient supporting means, and resilient supporting means disposed in said 50 receptacles capable of forcing the sides of the envelope apart.

2. In a device of the class described the combination of an innersole member having an elevated instep portion, a reinforcing plate member extending across said instep portion and a unitary support mechanism inserted between the plate and elevated portion, said unitary support mechanism comprising an envelope structure made from resilient material, metal plates 60 embedded in the upper and lower walls of said structure, spring members disposed between said walls to force the same apart, means integral with said plates and envelope walls to anchor 65 said spring members in position, and means co-operating between said reinforcing plate and said lower embedded plate to removably hold the support mechanism in position.

3. A device as set forth in claim 2 wherein the material of the envelope is so distributed about said spring member anchorage means as to prevent metallic contact between the spring members and upper and lower plates.

4. A device as set forth in claim 2 wherein said 75

envelope structure comprises upper and lower walls made from resilient material, said walls being joined at their edges, the material included in the joining portion being capable of co-
5 operating with said springs to assist the same to hold the walls apart.

5. A device as set forth in claim 2 wherein said envelope structure comprises upper and lower walls joined together throughout a portion
10 of their edges, the material included in the joining portion being of thicker cross section than that of the walls.

6. A device of the class described including in combination an innersole member for a shoe, the same having an elevated portion above the instep portion of the shoe and a unitary support element disposed below said elevated portion, said support element comprising an envelope structure having upper and lower walls
20 and springable members disposed between the walls capable of forcing the walls apart whereby to form a resilient support for said elevated portion of the innersole.

7. A device of the class described including in combination an innersole member having an elevated portion, a plate member attached to the innersole at each side of the elevated portion and a unitary support element removably inserted between said plate and innersole, said
30 support element comprising upper and lower

plate members attached to resilient material which extends beyond, and is joined at points spaced from the ends of the plates thereby forming a unitary structure, and spring members disposed between said plates.

8. A device of the class described including in combination an innersole member having an elevated portion, a plate member attached to the innersole at each side of the elevated portion and a unitary support mechanism removably inserted between said plate and innersole, said support element comprising upper and lower plate members attached to resilient material which extends beyond, and is joined at points spaced from the edges of the plates thereby forming a unitary structure, and spring members disposed between said plates.

9. A device of the class described including in combination an innersole member having an elevated portion, a plate member attached to the innersole at each side of the elevated portion, a support mechanism comprising a group of spring members arranged in spaced relationship and confined between separated upper and lower weight distributing members, said support mechanism being adapted to be placed between said elevated portion and plate member or removed therefrom as a unit without use of tools.
